UNITED STATES PATENT OFFICE

PHILIP BERGMANN, OF PHILADELPHIA, PENNSYLVANIA, ASSIGNOR TO COLUMBIA STEEL EQUIPMENT COMPANY, OF PHILADELPHIA, PENNSYLVANIA, A CORPORATION OF PENNSYLVANIA

POSTING TRAY

Application filed October 27, 1927. Serial No. 229,174.

This invention relates to office appliances and in particular to posting trays of the type used by banks and other business establishments for containing the account cards or 5 sheets.

An object of the invention is to provide a posting tray with a tilttable front.

Another object is to provide a tilttable front for posting trays, wherein means are included for locking the front in a vertical position.

Another object is to produce an efficient, strong and durable posting tray which may be economically constructed.

15 Other objects and advantages will herein-after appear.

The views of the drawings are:—

Figure 1 is an end view of a posting tray provided with a tilttable front constructed 20 according to my invention;

Figure 2 is a side view of the structure shown in Figure 1;

Figure 3 is a vertical longitudinal section taken approximately on the line 3—3 of Figure 1; and

Figure 4 is a plan of the bottom of the tilttable front of the posting tray.

Referring to the drawings, the posting tray has a bottom 1, a front end 2, a rigid side 3 30 and another side 4. These parts may be formed from pieces of sheet metal.

The side 3 is joined to the end 2, but the side 4 is so formed that it can be moved from a vertical position and slid into a pocket 35 5 formed beneath the bottom 1. When the side 4 is in the position under the bottom (see Figure 2), a secondary side 6, of less height than the side 4 but extending the length of the tray and fixed to the ends thereof, will prevent the contents of the tray from sliding laterally therefrom, as will be readily understood.

The end 2 has a handle 7 pivotally mounted thereon. Adjacent to the handle there may be fixed a frame 8 for receiving an index card (not shown) or the like.

The bottom 1 has feet 9, and these feet may be provided with resilient pads 10, as is customary in devices of this nature.

Suitably supported above the bottom 1 is another bottom 12.

Resting on the bottom 1 is a strip of metal formed with upstruck, inclined protuberances 13, to provide a serrated surface, the purpose of which is fully described in another application for United States Letters Patent filed by me September 17, 1927, Serial No. 220,171.

Above the protuberances 13, there is a rod 14, extending lengthwise of the tray and having one of its ends threaded to engage an opening in the tray, and having a nut or head 15 on the other end 2, as is customary in such trays.

The bottom 12 is slotted as shown at 16, Figure 3, to receive a spaced pair of L-shaped extensions 17 projecting laterally from the bottom of a tilttable front 18 with which the posting tray is provided. The extensions 17 70 prevent displacement of the front 18 from its position in the posting tray.

The front 18 is formed from a rectangular sheet of metal, and its upper horizontal edge is turned to form a bead 19.

The front extends considerably above the end and sides of the posting tray, and its outer surface, directly above the upper edge of the end 2, has welded thereto an outwardly projecting shelf 20. The outer edge of the shelf 20 is downturned so as to provide a flange 21.

A rib 22 is fixed to, and projects above the upper edge of the end 2. The rib is so disposed as to be engaged by the flange 21 83 when the front is in the position illustrated by Figure 2, to limit the inward swinging of the front.

The outer face of the front 18 has welded thereto a rectangular bracket 23, whose central portion is spaced from the front to provide a pocket in which is slidably mounted a latch 24.

The latch is made from a rectangular sheet of metal, the upper edge of which is bent outwardly to form a horizontal flange 25, constituting a handle, while the bottom of the latch is bent outwardly to form a flange 26 that is considerably longer than the flange 25.

When the front is in the position shown 133

by Fig. 2, the edge of the flange 26 abuts the inner face of the rib 22, and thus prevents the front from swinging outwardly. On the other hand, the flange 21 abuts the outer face of the rib and thereby prevents the front from swinging inwardly. In this way, the front is locked rigidly in position.

During the time the posting tray is not in use, the front may be disposed in the position shown by Figure 2, but when the posting tray is in use, the front may be disposed in the forwardly inclined position illustrated by Figure 3.

To shift the front from the position illustrated in Figure 2 to the position it is shown in by Figure 3, the flange 25 of the latch is grasped and the latch raised until the flange 26 overlies the top of the rib 22. The front 18 can now be manually swung forwardly, and the latch released. At this time the latch rests on top of the rib. When the position of the front is shifted from that shown by Figure 3 to that shown by Figure 2, the top of the front is pushed manually rearwardly, the latch falling by gravity when its flange 26 passes behind the rib 22.

The invention set forth herein is, of course, susceptible of various modifications and adaptations.

30 The invention claimed is:

1. In combination with a posting tray having an end formed with an upstanding rib, a front projecting above the end and pivotally mounted in the bottom of the posting tray, said front having a downwardly projecting flange for engaging the said rib to limit the inward swinging movement thereof, and a gravity latch engaging the said rib for normally preventing the outward swinging movement of the said front.

40 2. In combination with a posting tray having an end formed with an upstanding rib, a front projecting above the end and pivotally mounted in the bottom of the posting tray, said front having a downwardly projecting flange for engaging the said rib to limit the inward swinging movement thereof, and a gravity latch engaging the said rib for normally preventing the outward swinging movement of the said front, said latch being so disposed relative to the rib that when it is raised the front can be swung forwardly.

50 3. In combination with a posting tray having an end formed with an upstanding rib and a bottom, a tiltable front mounted on said bottom and having means fixed with relation thereto engaging said rib alternately with the front to limit swinging movement of said front, and means for locking the tiltable front 60 with the first-named means in engagement with said rib, said means being carried by the tiltable front and having engagement with said rib.

PHILIP BERGMANN.
